(57) CLAIM

The ornamental design for packaging with surface ornamentation, as shown and described.

DESCRIPTION

FIG. 1 is a front, left perspective view of a packaging with surface ornamentation embodying our new design;

FIG. 2 is front, right perspective view of the packaging shown in FIG. 1;

FIG. 3 is a front view of the packaging shown in FIG. 1;

FIG. 4 is a rear view of the packaging shown in FIG. 1;

FIG. 5 is a left side view of the packaging shown in FIG. 1;

FIG. 6 is a right side view of the packaging shown in FIG. 1;

FIG. 7 is a bottom view of the packaging shown in FIG. 1;

FIG. 8 is a top view of the packaging shown in FIG. 1; and,

FIG. 9 is a perspective view of the packaging of FIG. 1 in an unfolded state.

In FIGS. 1-9, the stippling represents no particular color or colors.

The broken lines in the drawings represent unclaimed environmental subject matter illustrating the design in use and form no part of the claim.
